UNITED STATES PATENT OFFICE.

MILLARD F. RICHARDSON, OF LIBERTY, INDIANA.

ROLLER-SKATE.

SPECIFICATION forming part of Letters Patent No. 336,437, dated February 16, 1886.

Application filed April 22, 1885. Serial No. 163,053. (Model.)

To all whom it may concern:

Be it known that I, MILLARD F. RICHARDSON, a resident of Liberty, in the county of Union and State of Indiana, have invented 5 certain new and useful Improvements in Roller-Skates, of which the following is a specification.

My invention relates to an improvement in roller-skates.

10 The object of my invention is to provide improved means for adjusting and locating the tension-spring interposed between the rocker-frame and the hanger frame or bracket.

Another object of my invention is to make 15 the rocker and hanger frame of but two parts or pieces, which reduces the depth or height of the combined frame, bringing the axle closer to the foot-board than when an interposed plate or piece is placed between the rocker and 20 hanger frame to regulate the tension.

Another object of my invention is to provide means for adjusting the tension and regulating the spring upon the outside of the bracket or hanger frame.

25 Another object of my invention is to provide suitable stops on the rocker-frame, which strike against the bracket to limit the rocking movement of the foot, all of which will be fully set forth in the description of the accompanying drawings, forming a part of this 30 specification, in which—

Figure 1 is a longitudinal cross-section of my improvement; Fig. 2, a rear elevation of the same; Fig. 3, a perspective view of the 35 tension-arm.

A represents the ordinary foot-board, made either of wood or metal; B, the rollers; C, the main axle; D, the hanger frame or bracket, secured to the foot-board in any desired manner. This hanger is provided with pendent arms 12, between which arms the rocker-frame F is pivoted in the following manner:

40 E represents the rocking or transverse axis of the frame, the forward point of which passes through and is supported in the pendent 1. Pendant 2 is provided with a vertical slot, 3, to allow vertical play of the rear end of the transverse axis E under the spring tension and adjustment.

45 4 represents a spring-seat formed on the upper side of the rocker-frame F.

5 5 represent coiled springs.

6 represents seats for the upper end of the coiled springs formed in the bracket D.

7 represents a ledge, preferably cast on and with the bracket D, and forming a rear extension thereof. It is made L-shaped, so as to give sufficient movement of the set-screw 8 to obtain the necessary spring-adjustment. Where thick foot-boards are employed, the 60 ledge 7 could be made lower, or the metal attached directly to the foot-board itself; but where metallic foot-boards are employed a deep or an elevated ledge is required in order to obtain the set-screw movement.

65 9 represents a tension-arm, which is provided with a flange, 10, at the upper end, and a screw-hole, 11.

12 represents a slot in the lower end of the arm, through which passes the transverse axis 70 E. The slot 3 in the pendent arm 2 is sufficiently deep to allow the axis E to rise and fall in the slot to allow the springs 5 to be adjusted to any desired degree of tension. The orifice in the pendent arm 1, through which 75 the pin E passes, must be sufficiently large to allow the axial pin E to rock as its rear end moves through the slot 3. The slot 12 in the tension-arm is made of sufficient depth to prevent the pin E from striking the tension-arm 80 under jars and strains of the springs, so as to avoid shock to the operator. When set-screw 8 is turned into the nut 7, it draws tension-arm 85 9 and the axial pin E upward, compressing springs 5, and thereby increasing their tension.

77 77 represent lugs formed upon the rear end of the rocker-frame F. They are formed by a rearward projection of the metal, preferably cast on and with the frame F, and they are a sufficient distance apart to form a channel or 90 groove for the pendent arm 2 to move freely in within the range of the desired movement of the rocker-frame F; but they are sufficiently close to the pendent arm 2 to strike the same and limit the canting or rocking motion of the 95 rocker-frame F, and thereby arrest the side or rocking movement of the foot. By employing the tension-arm 9 upon the rear side I avoid the use of an interposed plate between the springs and the rocker-frame, thereby reducing the distance from the foot-board to the axle C, bringing the skates lower down than 100

can be accomplished where an interposed adjusting-plate is employed.

I do not wish to limit myself to the use of the coiled springs 5 herein shown, as other 5 springs can be employed and accomplish the general purposes of invention herein shown and described.

I do not claim in this case anything described and claimed in my application filed March 2, 1885, Serial No. 157,525.

Having described my improvement, what I claim as my invention is—

1. In a roller-skate, the combination of bracket D, formed with pendent arms 1 and 2, 15 rocker-frame F, journaled on said arms by means of axis E, having a vertical play in arm 2, and the separate adjusting tension-arm 9, having an opening for the passage and support of one end of the axis E, and provided 20 with means for its adjustment, substantially as described.

2. A hanger device for a roller-skate, consisting, substantially, of the bracket D, rocker-frame F, springs 5, tension-arm 9, and set-screw 8, substantially as herein specified. 25

3. In combination with the bracket D, rocker-frame F, springs 5, tension-arm 9, provided with slot 12, and the pendent arm 2, provided with the slot 3, substantially as herein specified.

4. In combination with the bracket D, having the slotted pendent arm 2, the slotted tension-arm 9, engaging with axis E, and the set-screw 8, for adjusting the springs 5, substantially as herein specified.

5. In combination with bracket D, having pendent arms 1 and 2, rocker-frame F, journaled between said arms, and formed with lugs 7 on its under face on opposite sides of arm 2, to permit movement of the latter, and 40 coiled springs 5, fitting in bracket D, and frame F, substantially as and for the purposes described.

In testimony whereof I have hereunto set my hand.

MILLARD F. RICHARDSON.
